CLAIM

The ornamental design for a juice extractor barrel, as shown and described.

DESCRIPTION

1. Juice extractor barrel

FIG. 1.1 is a front, left and top axonometric view of the juice extractor barrel showing my new design;

FIG. 1.2 is a front elevation view thereof;

FIG. 1.3 is a back elevation view thereof;

FIG. 1.4 is a left elevation view thereof;

FIG. 1.5 is a right elevation view thereof;

FIG. 1.6 is a top plan view thereof; and

FIG. 1.7 is a bottom plan view thereof.

The design is a juice extractor barrel for grinding food materials such as vegetables and fruits and extracting the juice thereof. The evenly spaced dashed broken lines depict portions of the juice extractor barrel that form no part of the claimed design.
